(57) **CLAIM**

The ornamental design for a medical powder ejection device, as shown and described.

DESCRIPTION

FIG. 1 is a front elevational view of a medical powder ejection device showing our new design, the rear elevational view being a mirror image thereto;

FIG. 2 is a top plan view thereof, the bottom plan view being a mirror image thereto;

FIG. 3 is a right side elevational view thereof;

FIG. 4 is a left side elevational view thereof; and,

FIG. 5 is a perspective view thereof.

1 Claim, 5 Drawing Sheets
